MACHINE FOR COMPRESSION OF GASES,
VAPORS, AND LIQUIDS

Arthur C. Layton, Tyler, Tex.

Application August 27, 1951, Serial No. 243,809

5 Claims. (Cl. 230—108)

1

This invention consists of a machine for the compression of gases, vapors, and liquids. It is especially designed as a modification of my pending application Serial No. 235,040 for a machine for the compression of more or less dense gases and vapors. The present invention is modified to permit compression of lighter, or less dense gases than the former. It is also designed for use as a large capacity machine.

One object of the invention is to provide a machine for the compression of light gases and vapors by simple means.

Another object is to provide means for compression of gases and vapors to higher pressures than can be obtained by the machine described in Serial No. 235,040.

An important object is to provide automatic, self-priming, means for the machine described in my aforesaid pending application.

One of the most important objects is to provide means for cooling the compressor from external cooling sources.

A preferred form of the invention is shown on the attached drawings in which:

Figure 1 shows a vertical section taken along the central axis of my machine;

Figure 2 is a horizontal cross-sectional view in which the upper right hand quadrant shows a section taken along the lines A—A in Figure 1; the upper left hand quadrant shows a section view along the line B—B of Figure 1; the lower left hand quadrant shows a section view along the line C—C of Figure 1; and the lower right hand quadrant shows a section view along the line D—D of Figure 1;

Figure 3 shows a plan view of the priming pump contained in the lower section of the compressor;

Figure 4 shows an elevation of the pump shown in Figure 3, with a portion broken away to show a partial cross-section taken in the plane of Figure 1.

Figure 5 shows an elevation of the rotating sleeve which forms driving means for the priming pump, with a portion broken away to show a partial cross-section taken in the plane of Figure 1.

Figure 6 shows an elevation of the protecting sleeve, dispersion ring, and inclosure for the rotating sleeve shown in Figure 5 and the priming pump shown in Figure 4, with a portion broken away to show a partial cross-section taken in the plane of Figure 1.

Figure 7 shows a horizontal section taken along the line 7—7 of Figure 6;

2

Figure 8 shows an elevation of the central pipe and supporting means for the rotating sleeve and priming pump removed from the compressor; and

5 Figure 9 shows a modification of the invention to utilize external cooling means.

The invention consists of a cylindrical body 11 comprising an upper and a lower half, the two halves being fastened together to form a hermetically sealed vessel. Communicating pipes 12, herein referred to as the suction pipe, and 13 (shown by dotted lines), herein referred to as the discharge or hot gas line, are secured to the body 11, and connect to the evaporator and condenser, respectively. The discharge pipe 13 is formed substantially the same as 12. The lower half of the body 11 is formed with a pocket or sump 14 which projects axially down from the body. The top of the sump is formed with a plurality of axially disposed ports 15 spaced radially about the top of the sump and communicating with the interior of the body 11.

A vertical pipe 16 is disposed co-axially of the body 11, communicates at its upper end with the suction pipe, and is connected at its lower end to the sump 14 by means of a central opening 37 in the top of the sump. This pipe 16 is formed with a partition 17 located at its approximate mid-section, which divides the pipe into an upper chamber 18 and lower chamber 19. The upper end of the pipe 16 is secured to the body 11 by means of a locking nut 20 fitted into an annular recess near its top. The connection between the body 11 and the pipe 16 is hermetically sealed by means of the gasket 21 disposed axially between the nut 20 and the body 11. The pipe 16 is formed with a horizontal exterior groove encircling it at the portion containing the partition 17, midway between the chambers 18 and 19, and forming a space 23 around the circumference of the pipe 16. This pipe is formed with a plurality of radially disposed ports 22 located at the extreme lower end of the chamber 18 and leading to the space 23, and a corresponding group of radially disposed ports located in the upper section of the chamber 19, also leading to the space 23 and designed to receive the nozzles 24.

A check valve 25 is located at the extreme upper end of the chamber 18 in an enlarged section of the pipe 16. This check valve comprises upper and lower guides 57, 58, respectively, and a movable disc 59 formed on a rod 60 inserted between the upper and lower guides and biased upward by a spring 61. The upper guide 57 of the check valve 25 forms locking means for se-

curing the check valve in position. A gasket 26 between the upper guide and the shoulder formed in the pipe 16 hermetically seals the chamber 18 when the check valve is in the closed position.

An elongated sleeve 27 surrounds the upper section of the pipe 16, forms a bearing surface with it, and is free to rotate about it. Upward axial movement of the sleeve 27 is prevented by a shoulder 28 formed in the upper section of the body 11. The lower end of the sleeve 27 projects downwardly, incloses a portion of the space 23 formed by the groove in the pipe 16, and carries a radially extended flange 29. This flange 29 is securely fastened to and supports a disc 30, which therefore rotates with the sleeve 27.

Another sleeve 31, formed substantially the same as the sleeve 27 except that the flanged portion is located at its upper end, encircles the lower part of the pipe 16. The flanged end of the sleeve 31 extends upwardly to the space 23, and is securely fastened to and supports the disc 32, the sleeve and disc being free to rotate about the pipe 16. The discs 30 and 32 are disposed radially of the pipe 16, encircle portions of the space 23, and are axially opposed.

A plurality of curved elements 33 are regularly spaced between the discs 30 and 32, said elements extending radially, and curving tangentially, to the periphery of the discs 30 and 32, the elements being secured between and to the discs by any convenient means, and forming therewith a plurality of elongated ports 34 constituting communicating means between the space 23 and the interior of the body 11. The assembly, consisting of the sleeves 27 and 31, the discs 30 and 32, and the elements 33, is thus free to rotate as a unit about the pipe 16, the pipe forming a bearing surface and supporting means for the assembly.

The armature, or rotor 35 of an electric motor, is formed as a ring secured to the sleeve 27 and disposed concentrically therewith and is located axially between the flange 29 and the shoulder 28, the rotor thus forming a part of the assembly as outlined above.

A ring 36 rotatably encircles the lower end of the pipe 16. The pipe forms a bearing surface for the ring 36, which is disposed axially between the lower end of the sleeve 31 and a shoulder 40 formed in the upper wall of the sump 14 surrounding the central opening 37 of the sump 14. The ring 36 is provided with a plurality of radially projecting arms 38 which are inclined helically of the ring 36 and constitute a propeller. The ring 36 is provided with serrations 39 formed radially on its upper surface which engage with corresponding serrations 39a formed radially on the lower end of the sleeve 31 so that the sleeve 31 may be moved upwardly without removing the ring 36, but may not be rotated unless the ring 36 rotates with it. The ring 36 thus forms a part of the rotatable assembly and serves as a supporting means to prevent axial movement downwardly of the assembly, with its lower face forming a bearing surface with the body 11 at the shoulder 40 surrounding the central opening 37 of the sump 14.

A diverter ring 41 carrying an outer flange 42 encircles the discs 30 and 32. Immediately therebelow a guide ring 44 in the shape of a centerless bowl carries a corresponding outer flange 45 which registers with the flange 42 of the ring 41. The body 11 is formed in upper and lower halves and the interior sides of the mating

edges of these halves are cut back to define a horizontal annular groove in which the flanges 42 and 45 are clamped between the upper and lower halves of the body 11. Registering ports 43 in the flange 42 and 46 in the flange 45 constitute a passageway between the upper and lower halves of the chamber enclosed by the body 11.

A plurality of cylindrical perforated sleeves 48 of varying diameter, disposed axially of the body 11 and spaced radially, are suspended from the guide ring 44 and project downwardly to the bottom wall of the body 11. The lower edges of the rings 48 are designed to permit fluid to flow along the bottom wall of the body 11 to the ports 15.

An elongated sleeve 49 formed with a flared upper end encircles the sleeve 31, and is stepped outwardly at its lower end 50, encircling the ring 36 and its projecting arms 38. This lower end 50 is secured in a recess 51 formed axially of the lower section of the body 11, and the top of the step constitutes a radial flange 52 pierced by a plurality of guide ports 53 registering with the ports 15 formed in the sump 14. The flange 52 thus forms an enclosure for the arms 38 of the ring 36.

A frusto-conical dispersion plate 54 is affixed to and supported by the midsection of the sleeve 49, the plate extending radially therefrom and sloping downwardly to the inner cylindrical surface of the nearest perforated sleeve 48.

A sleeve 55 containing the field or stator of an electric motor is affixed to the interior of the upper half of the body 11 and encircles the rotor 35 affixed to the sleeve 27.

A terminal plug 56 is located at any convenient point in the wall of the body 11, and serves to form sealing and insulating means for inserting electric wires for connection to the electric motor. These may be of standard manufacture and are not claimed as a part of this invention.

In operation (after making suitable connections with the condenser, receiver, and evaporator, to form a hermetically closed system with the compressor) the system is completely evacuated of all air, moisture, and noncondensable gases, after which a suitable dehydrated lubricating oil is added to the compressor until the oil level covers the lower portion of the body to the approximate height of the lower edge of the dispersion plate 54. Refrigerant is now added to the system in the desired quantity, and pressures reach a state of equilibrium in all parts of the system, including the compressor. Liquid refrigerant is usually added at the receiver—the remaining portions of the system contain only refrigerant vapor at the beginning—the vapor condensing to a liquid under suitable pressure and temperature conditions.

The check valve 25 remains closed as long as the pressure on the upper and lower sides is balanced, the spring under the check valve forcing the check valve upwardly against its seat—the spring being just strong enough to overcome the weight of the valve.

The motor is then started by external starting means. The serrations 39 of the ring 36 are engaged by the registering serrations 39a formed on the lower end of the sleeve 31 thus causing the ring 36 to rotate with the assembly. The arms 38 of the ring 36 are inclined helically to form a propeller which, when rotated, exerts a downward thrust upon the oil which engulfs the ring and projecting arms 38, the oil being drawn through

the channelling ports 53, and forced downwardly through the ports 15, thus creating a higher pressure in the sump 14 than exists in the chamber formed by the body 11. The higher pressure in the sump will cause the oil level to rise in the chamber 19. As the pressure in the sump 14 and the chamber 19 continues to rise due to pressure exerted by the propeller 38, oil will be discharged through the nozzles 24 and picked up by the rapidly rotating elements 33 and directed into the elongated ports 34, through which the oil is forced radially by the centrifugal effect given it by the rapidly rotating elements. The quantity of oil thus discharged by the nozzles into the elongated ports 34 will be a function of the pressure difference between the sump 14 and the space 23. Other variables influence the rate of discharge and these will be discussed as the description progresses.

Oil centrifugally ejected from the ports 34 is thrown tangentially against the sloping wall of the ring 41 and is spread thinly and its velocity dissipated in a swirling motion as it settles by gravitational effect to the guide ring 44 and falls to the dispersion plate 54 where it is directed through the perforated sleeves 48 and settles to the lower portion of the body 11 for recycling by the propeller 38.

It is especially emphasized that drops of oil discharged from the ports 34 also eject a portion of the refrigerant vapor contained in the port. A slight lowering of pressure in the space 23 and the ports 34 is thus produced by ejection of oil from the ports 34, the reduction in pressure in the space 23 thus creating a greater pressure differential between the chamber 19 and the space 23. This condition will increase the amount and velocity of oil being discharged by the nozzles 24. As rotation continues a constantly increasing pressure differential is built up between the chamber 19 and the space 23. A reduction in pressure in the space 23 will likewise produce a pressure reduction in the chamber 18 and permit the refrigerant vapor contained in the suction pipe 12 to overcome the check valve 25 and flow into the chamber 18, through the ports 22, into the space 23, and into the rotating ports 34 where it is ejected into the interior of the body 11 by the slugs of oil being discharged from the ports 34. The oil and refrigerant vapor now pass over the dispersion plate 54, through the perforated sleeves 48, the oil settling to the lower portion of the body 11 while the refrigerant vapor continues through the remainder of the perforated sleeves 48, where oil particles are scrubbed out, the vapor then rising and passing through the ports 46 and 43 to the upper section of the body 11 and out through the discharge pipe 13 to the condenser (not shown).

Additional vapor drawn in through the suction pipe 12 and discharged into the interior of the body 11 will produce a still higher pressure differential between the chamber 19 and the space 23, thus producing a higher velocity and greater discharge of oil from the nozzles 24. Once the pressure difference is established the propeller 38 will not be required to cause a circulation of oil. The propeller is thus an exciting means to start the circulation of oil. It is to be observed that the downward thrust upon the oil by the propeller 38 will in turn cause an upward thrust against the rotating assembly thus reducing wear of the bearing surface of the ring 36 and the shoulder 40.

The oil thus far has been considered as an entity, and the refrigerant vapor as a separate

entity. Actually, the oil will absorb a large part of the refrigerant in either the liquid or gaseous state, the amount absorbed being a function of the pressure and of the temperature. The weight of oil absorbed will vary directly with the pressure and inversely as the temperature. This absorption forms an important part of this invention.

As the oil, under relatively high pressure and containing a relatively high percentage of refrigerant vapor, emerges from the nozzles at high velocity, it will experience a sudden reduction of pressure in the space 23, whereupon the refrigerant contained in the oil will expand and break the oil up into foam. Since the foam will occupy a larger volume than the oil, it will expand radially of the port 34 to form a moving piston to eject gas vapor outwardly through the port 34 ahead of the slug of oil foam. The number of ports 34 should be greater than the number of nozzles 24 in order to trap a relatively large volume of vapor in the ports 34 between the pistons of foam. The nozzles should be designed to utilize the expansive property of the refrigerant vapor contained in the oil to obtain the maximum sputting velocity of the oil. This will increase the pressure in the body 11 and reflect an increased efficiency of the machine. The amount of oil discharged from the nozzles should be limited by the pressure desired in the body 11. Overall efficiency of the machine would require a minimum of oil to be discharged at a maximum velocity. Now since the velocity will be a function of the pressure it is pointed out that the exciter pump 38 can be designed to give any desired pressure in the sump 14 regardless of the pressure in the body 11. The exciter pump in this case would function as an auxiliary to normal operation to effect a higher pressure in the sump, or system.

Since a portion of the heat of compression of the vapor in the ports 34 will be absorbed by the oil foam, a reduction of compression temperature and pressure will be effected. This in turn will effect an economy in the work of compression by dissipation of heat by the circulating oil. External cooling of the oil will increase the efficiency of the system. This may be accomplished by simple means without departing from this invention, as follows:

An inner partition 62 is formed in the sump 14, thus sealing the sump 14 and the lower passageway of the chamber 19 from the interior of the body 11. An outlet port 63 is formed in the outer wall of the sump 14, and an inlet port 64 formed in the bottom wall of the sump 14 within the confines of the inner partition. The outlet port and inlet port are connected to an external cooler, whereby the pump will force oil through the cooler, and return it to the sump and chamber 19 as before. The same pressure difference will be maintained as before—neglecting the frictional losses produced by the cooler. This modification is shown in Figure 9 of the attached drawings.

While a particular preferred embodiment of this invention has been illustrated and described, it will be apparent to those skilled in the art that various changes and modifications may be made without departing from the invention, and it is intended in the appended claims to cover all such changes and modifications as may fall within the true spirit and scope of this invention. For example—the exciter pump has been shown as an axial flow pump. However, a radial flow pump could be used with slight modifications.

What I claim is:

1. A fluid compressor comprising a vertical cylindrical casing enclosing a pressure chamber, upper and lower cylindrical chambers located within and along the central axis of said casing, a fluid inlet from outside said casing to said upper chamber, at least one lower passage and a plurality of radially spaced upper passages connecting said lower chamber and said pressure chamber, nozzles constituting restrictions in said upper passages, liquid in said lower chamber, orifices radially spaced about the bottom of said upper chamber communicating with said pressure chamber and said upper passages outwardly of said nozzles, a sleeve mounted for rotation about said upper and lower chambers, vanes at the lower end of said sleeve constituting a propeller for forcing liquid from said pressure chamber into said lower chamber, ducts radiating spirally from said sleeve opposite said adjacent orifices and nozzles, and means for rotating said sleeve, ducts and propeller.

2. A fluid compressor as claimed in claim 1 in which said casing carries a frusto-conical upwardly converging diverter ring encircling the outer ends of said radiating ducts, a downwardly converging guide ring immediately therebelow and a plurality of perforated sleeves coaxial with said casing extending downward from said guide ring.

3. A compressor as claimed in claim 2 in which said casing carries a substantially solid protective sleeve encircling the propeller carrying sleeve, and said protective sleeve carries a dispersion plate extending downwardly and outwardly to the nearest perforated sleeve, intermediate of its height.

4. A compressor as claimed in claim 1 in which said propeller is mounted on a separate ring rotatable about said lower cylindrical chamber and carries on its top serrations separably engaging corresponding serrations on the bottom of said sleeve.

5. 10 15

20 25

5. A fluid compressor comprising a casing enclosing a pressure chamber, an inlet orifice in said casing for admitting fluid to be compressed to the chamber, an outlet orifice in said casing, a sump at the bottom of said casing, a liquid in said sump, a wall within said casing separating said pressure chamber and said sump, said wall having a vertical cylindrical portion located centrally of said casing, a lower passage in said wall and a propeller in said lower passage, at least one upper passage in the cylindrical portion of said wall and a nozzle in said upper passage, conduit means connecting said inlet and said upper passage, a rotatable sleeve encircling the cylindrical portion of said wall, spirally radiating ducts carried by said sleeve and registering vertically with said upper passage, and means for rotating said sleeve, ducts and propeller so as to circulate said liquid between said pressure chamber and sump and thence through said upper passage and radiating ducts whereby liquid ejected from said nozzle serves to draw fluid through said conduit and inlet orifice into said pressure chamber.
